UNITED STATES PATENT OFFICE.

FREDERICK B. DUNCAN, OF AKRON, OHIO.

MEANS FOR ADJUSTING DYNAMOS OR MOTORS ON THEIR BED-PLATES.

SPECIFICATION forming part of Letters Patent No. 697,998, dated April 22, 1902.

Application filed February 21, 1902. Serial No. 95,128. (No model.)

To all whom it may concern:

Be it known that I, FREDERICK B. DUNCAN, a subject of Edward VII, King of England, residing at Akron, in the county of Summit and

5 State of Ohio, have invented a certain new and useful Improvement in Means for Adjusting Dynamos and Motors on Their Bed-Plates, of which the following is a specification.

My invention has relation to improvements 10 in means for adjusting and retaining dynamos and motors on their bed-plates.

In ordinary methods of construction the dynamo or motor is secured on its bed-plate by common round bolts that pass through holes 15 in the feet of the motor or dynamo and are drawn tight by nuts bearing on the latter. When the belt that drives the armature becomes loose, the bolts are loosened and the motor or dynamo drawn back by a screw for 20 the purpose. The effect of drawing the belt tight and the constant lateral strain on the shaft of the machine in one direction tends to twist it, thereby tending to cause the belt to run off from the pulley and affecting the 25 accurate alinement of the machine, inasmuch as the bolts are loose in the slot and only bear on the sides of the slots.

The object of my invention is to overcome this difficulty and by a simple device cause 30 the bolts to be self-centering and the motor or dynamo self-alining whenever tightened.

To the accomplishment of the aforesaid object my invention consists in the peculiar and novel construction, arrangement, and combination 35 of parts hereinafter described and then specifically pointed out in the claims, reference being had to the accompanying drawings, which form a part of this specification.

40 In the accompanying drawings, in which similar reference-numerals indicate like parts in the different figures, Figure 1 is a plan of my improved bed-plate with the dynamo or motor suggested by dotted lines; Fig. 2, a section of the same at the line xx ; and Fig. 3 and Fig. 4, plan and side elevations, respectively, of the retaining-bolts.

Referring to the figures, 1 is the bed-plate, provided with slots 4, that taper at the side from below. The feet 3 (suggested by dotted 50 lines) of the dynamo or motor have holes through which the round portions of the bolts pass and are secured by nuts (indicated by dotted lines) in the usual manner. The bed-plate and feet are provided with the usual adjusting screw and nut (shown in dotted lines) for moving the latter on the former. The bolts 5, by which these two parts are united, have pyramidal heads that accurately fit the sides of the slots 4. When these bolts are 55 drawn tight by their nuts, as in originally setting up the machine, or after they have been loosened to permit the feet to be drawn back, as just stated, the rectangular pyramidal heads draw firmly into their seats and accurately center the round parts in the slots, thus at all times securing the feet against any twisting on its bed from lateral strain of the belt or otherwise and insuring its accurate alinement at all times. 70

Having thus described my invention, what I claim, and desire to secure by Letters Patent, is—

1. An improved bed-plate for dynamos and motors having slots tapering from below, bolts 75 with pyramidal heads to retain the dynamo or motor, substantially as shown and for the purpose specified.

2. The combination with a bed-plate for dynamos and motors, having slots with sides 80 sloping outward from above, of bolts for retaining a dynamo or motor thereon having heads adapted to fit the sides of said slots, substantially as shown and described.

In testimony that I claim the above I here- 85 unto set my hand in the presence of two subscribing witnesses.

FREDERICK B. DUNCAN.

In presence of—

C. P. HUMPHREY,
C. E. HUMPHREY.
